DESIGN FOR AN EMBALMING MACHINE

Thomas A. Gilmore and Louis Junod,
Brooklyn, N. Y.

Application December 11, 1940, Serial No. 97,267

Term of patent 14 years

To all whom it may concern:

Be it known that we, Thomas A. Gilmore and Louis Junod, citizens of the United States, residing at Brooklyn, in the county of Kings and State of New York, have invented a new, original, and ornamental Design for Embalming Machines, of which the following is a specification, reference being had to the accompanying drawing, forming part thereof.

Fig. 1 is a side elevational view of an embalming machine, showing our new design;

Fig. 2 is a top plan view thereof;

Fig. 3 is an end elevational view looking from the left on Fig. 1; and

Fig. 4 is an end elevational view looking from the right on Fig. 1.

We claim:

The ornamental design for an embalming machine, as shown.

THOMAS A. GILMORE.
LOUIS JUNOD.
